UNITED STATES PATENT OFFICE.

WADE HAMPTON DE FONTAINE, OF NEW YORK, N. Y.

DESIGN FOR A CARBURETER.

45,591.

Specification for Design.

Patented Apr. 14, 1914.

Application filed January 24, 1914. Serial No. 814,249. Term of patent 3½ years.

To all whom it may concern:

Be it known that I, WADE HAMPTON DE FONTAINE, a citizen of the United States, residing at the city of New York, in the county of New York, State of New York, have invented a new, original, and ornamental Design for Carbureters, of which the following is a specification, reference being had to the accompanying drawing, forming part thereof.

Figure 1 shows a carbureter in elevation and Fig. 2 in plan embodying my new design.

I claim:

The ornamental design for a carbureter as shown.

In testimony whereof I have hereunto set my hand in the presence of two subscribing witnesses.

WADE HAMPTON DE FONTAINE.

Witnesses:

FRITZ V. BRIESEN,
FRED A. KLEIN.
